(57) **CLAIM**

(22) Filed: **Sep. 15, 2012**

The ornamental design for a detachable mounting unit of a device for measuring parameters for manufacturing spectacle lens, as shown and described.

(30) **Foreign Application Priority Data**

DESCRIPTION

Jun. 28, 2012 (KR) 30-2012-0031556

FIG. 1 is a perspective view of a detachable mounting unit of a device for measuring parameters for manufacturing spectacle lens, showing my new design;

(51) **LOC (10) Cl.** **10-04**

FIG. 2 is a front view thereof;

(52) **U.S. Cl.**

FIG. 3 is a rear view thereof;

USPC **D10/80**; D8/367

FIG. 4 is a left side view thereof;

(58) **Field of Classification Search**

FIG. 5 is a right side view thereof;

USPC D10/80; 24/3.12, 545, 563, 546-556,
24/570, 571, 907, 369-371; 248/690, 215,
248/301, 304-308, 339; D8/367-371,
D8/394-396

FIG. 6 is a top plan view thereof; and

See application file for complete search history.

FIG. 7 is a bottom plan view thereof; and,

(56) **References Cited**

FIG. 8 is a perspective view showing an example of the usage
of the detachable mounting unit of the device for measuring
parameters for manufacturing spectacle lens in which the
detachable mounting unit is coupled to a tablet computer.
